UNITED STATES PATENT OFFICE

PATRICK CORCORAN, OF MEMPHIS, TENNESSEE

SCAFFOLD LIFT

Application filed October 16, 1929. Serial No. 400,103.

My invention relates to a scaffold hoist for operation by man power.

The objects of my invention are to provide a device of this class which is new, novel, 5 practical and of utility; which will be speedy in operation; which will be safe; which will be strong and durable; which will be operated with little effort; which may be operated by foot power; which will be efficient in accomplishing all of the purposes for which it is intended.

My invention provides a means which will lift a number of men together with their tools in an easy manner and at the same time, leave 15 the operator's hands free for other uses.

With these and other objects in view as will more fully appear, my invention consists in the construction, novel features, and combination of parts hereinafter more fully 20 described, pointed out in the claims hereto appended, and illustrated in the accompanying two-sheet drawing, of which,

Figure 1 is an elevational view of the device from the end of a scaffold;

Figure 2 is an elevational view of the device from the side of a scaffold; and

Figure 3 is a perspective view of a scaffold showing four of the devices operably disposed thereon.

Like characters of reference designate like parts in all the figures.

It is understood that various changes in the form, proportion, size, shape, weight and other details of construction, within the scope 35 of my invention may be resorted to without departing from the spirit or broad principle of my invention and without sacrificing any of the advantages thereof; and it is also understood that the drawings are to be interpreted as being illustrative and not restrictive.

One practical embodiment of the invention as illustrated in the drawings comprises the following:

My device is shown supporting the boards 3 of a scaffold. Said device has a rectangular metal frame 4 provided across its top member with a roller 5. The side members of the frame 4 are provided with a plurality of 40 aligned pairs of bearings 6 in each pair of

which are, respectively, journaled shafts 7, 8 and 9. The lower cross member of said frame 4 is attached to said scaffold boards 3 by a pivotal means 25. A cable 15 is provided, and as shown in Figure 1, is to be securely 55 fastened to a suitable holding means or beam 26 which is properly positioned with relation to where it is intended to have the scaffold located.

Mounted adjacent each end of said shaft 8 are toothed wheels 10 and 11. Said wheel 11 meshes with a toothed wheel 12 which is mounted in alinement with said wheel 11 upon the lower shaft 9 and is rigidly keyed thereto. Said shaft 8, between said wheels 10 and 11, is provided with a rope drum 14 to which one end of said cable 15 is attached in a usual manner. Said drum, when turned, is adapted to wind, or unwind, said cable 15 for raising and lowering the scaffold. It will be noted that said rope 15 will slidably contact said roller 5 and will thus be prevented from undue wear. Loosely mounted upon the said shaft 9 is a lever or arm 16 which is adapted at its free end to be reciprocated upward and downward. Pivotaly disposed upon said lever 16 is a foot operable pawl 18, one end of which is adapted to engage between teeth of said wheel 12 and when so engaged acts as a medium for turning said wheel 12 and axle 9 in bearings 6. When wheel 12 is thus turned its teeth upon the upper portion of the wheel which mesh with the teeth of said wheel 11 cause the rotation of said wheel 11 and consequently cause the rotation of said shaft 8 and rope drum 14. For the purpose of raising said lever arm 16 I provide a retrieving spring 19 which is attached to said lever 16 at its lower end and to said shaft 8 at its upper end. With each operation of the lever 16 it will be seen that pawl 18 will cause wheels 11 and 12 to move to the extent of as many teeth as the movement of the lever 16 causes it to make. It will further be understood that said wheel 10 will also be caused to move because of the fact that it is rigidly keyed to said shaft 8. Rigidly positioned upon said shaft 7 in alinement vertically with said wheels 10 and 11 I provide respective pawls 20. Said pawls 20 are

60

65

70

75

80

85

90

95

100

provided with a head 23 and a handle or lever arm 24 which are adapted to be hand operated for setting said wheels 10 and 11 against rotation. By providing a pawl for each of said wheels 10 and 11 I thus secure greater safety against accidents and danger. Springs 27 are provided to lock said pawls 20 against undue or unauthorized movement.

It will be understood that, if desirable, a 10 duplicate of lever 16 and its accompanying co-operating parts may be provided for the said toothed wheel 10. I prefer, however, to have only one operated at a time. The permitting of the lever to be operated by the foot leaves 15 the use of the hands for the operating of said pawls 20 or for other uses, when needed. In operation lever arm 16 is held by said retrieving spring 19 in a position as indicated in Figure 2. Lever 16 is pushed downward 20 by the foot against the tension of said spring 19 causing wheel 12 meshing with wheel 11 to rotate wheel 10 and rope drum 14, thus winding up said rope 15. The foot is removed and retrieving spring 19 immediately 25 returns said lever 16 to its original position. The contacting end of said pawl 18 slips over the edges of the teeth on said wheel 12. When the scaffold has thus been raised to a desired height pawls 20 are slipped into engagement with the teeth in said wheels 10 and 11 and spring 27 is clamped about handle 24 thus anchoring said wheels 10 and 11 against any undue rotation.

Obviously, the invention is susceptible of 35 embodiment in forms other than that which is illustrated in the accompanying drawings and described herein, and applicable, for the uses and purposes other than as detailed, and I therefore consider as my own all such modifications and adaptations and other uses of 40 the form of the device herein described as fairly fall within the scope of my invention.

Having thus described my invention what is claimed and desired to be secured by Letters Patent, is:

1. In a scaffold lift a frame adapted to hold various parts of the mechanism and to support a platform, bearings disposed about the frame, a first, second and third shaft 50 mounted in said bearings, a toothed gear wheel on each end of said second shaft, a cable drum supported upon said second shaft between said gear wheels, a smaller toothed wheel mounted on one end of said third shaft 55 and having its teeth meshing with the teeth on one of said larger toothed gear wheels, a lever on said third shaft, a foot operable pawl movably anchored to said lever and adapted to engage the teeth on said smaller 60 gear wheel, said lever, pawl and smaller wheel being manually operated for turning said larger wheels and said cable drum, a spring for re-positioning said lever and foot pawl, said cable drum being adapted for co- 65 operation with a suitably anchored cable for

raising and lowering said device, a friction roller on said frame for contacting said cable, a pawled lever adjacent each end of said first shaft for engaging the teeth of the toothed gear wheels on opposed sides intermittently 70 as the larger gear wheels are operated for raising the frame.

2. In a device as set forth, a rectangular frame, bearings in pairs carried thereby in alinement laterally, three shafts mounted respectively in said bearings, a toothed smaller gear wheel mounted on the lowermost shaft and operable therewith, larger toothed gear wheels mounted on the medial shaft operable by said smaller toothed gear wheel and operating a cable drum, a cable drum mounted with said larger gear wheels on said medial shaft, a cable connected to said drum for raising and lowering said frame, hand lever pawls carried by the uppermost shaft and operable therewith for engaging the teeth on said larger wheels for securely holding and releasing said scaffold, lever operated mechanism having a foot operated pawl thereon for actuating said smaller wheel, said smaller wheel meshing with and rotating said larger wheel, and spring means for operatively re-positioning said lever and pawl upon release. 80

3. In a scaffold lift, a frame adapted for holding various parts of the mechanism, having side vertical members and top and bottom horizontal members, bearings about the frame disposed laterally in pairs, a first, second and third shaft mounted respectively in said pairs of bearings, a toothed gear wheel 100 mounted adjacent each end of said second shaft, a cable drum between said wheels integral with said shaft, a cable adapted for winding and unwinding on said drum and to be suitably anchored thereabove, a hand operated pawl adjacent each end of said first shaft adapted to engage between the teeth of and for holding and releasing said toothed wheels, an additional and smaller toothed wheel on said third shaft having its teeth 105 meshing with the teeth of one of said larger toothed wheels, a lever on said third shaft, a foot operable pawl movably mounted on said lever adapted to engage the teeth of said smaller toothed wheel, said lever, pawl, and smaller wheel being adapted to operate one of said larger toothed wheels and to turn said drum and the other larger toothed wheel for winding and unwinding said cable, a spring having one end anchored to said lever and its other end anchored to said second shaft for re-positioning said lever and foot operable pawl when released, and a friction roller on said top horizontal portion of, 110 said frame for contacting said cable the bottom horizontal portion of said frame being adapted to support a scaffold. 115

4. A scaffold lift, having in combination, a frame adapted for holding various parts of the mechanism, having side vertical mem- 120

125

bers and top and bottom horizontal members, bearings about the frame disposed laterally in pairs, a first, second and third shaft mounted respectively in said pairs of bearings, a toothed gear wheel mounted adjacent each end of said second shaft, a cable drum between said wheels integral with said second shaft, a cable adapted for winding and unwinding on said drum and to be suitably anchored thereabove, a hand operated pawl adjacent each end of said first shaft adapted to engage between the teeth of and for holding and releasing said toothed gear wheels, an additional and smaller wheel mounted on said third shaft having teeth meshing with the teeth of one of said larger toothed wheels, a foot operable lever on said third shaft, a foot operable pawl movably mounted on said lever and adapted to engage the teeth of said smaller toothed wheel, said lever, pawl, and smaller wheel being adapted to operate one of said larger toothed wheels and to turn said drum and the other larger toothed wheel to wind and unwind said cable, a spring having one end anchored to said lever and its other end anchored to said second shaft for re-positioning said lever and foot operable pawl, and a friction roller on said top horizontal portion of said frame, the bottom horizontal portion of said frame being adapted to support a scaffold.

PATRICK CORCORAN.
